UNITED STATES PATENT OFFICE.

ALBERT G. FELKER, OF MARSHFIELD, WISCONSIN.

JOINT FOR WELL-CASINGS.

1,044,873.

Specification of Letters Patent. Patented Nov. 19, 1912.

Application filed November 20, 1909. Serial No. 528,102.

To all whom it may concern:

Be it known that I, ALBERT G. FELKER, a citizen of the United States, residing at Marshfield, in the county of Wood and State 5 of Wisconsin, have invented a new and useful Joint for Well-Casings, of which the following is a specification.

This invention is an improved joint for sectional sheet metal tubes and is intended 10 more particularly for well casings although it is adapted to many uses.

The primary object of the invention is to provide a joint between the members of a sheet metal tube which will be so constructed 15 as to avoid the presence of internal shoulders or projections which are liable to be struck by the sharpened edges of drills passing through a well casing in the sinking 20 of a well or by pump rods or other devices which may be subsequently arranged and operated within the tube or casing.

In the use of constructions heretofore provided, much annoyance has been caused by the drill or the pump rod or other elements 25 striking against abrupt internal projections or shoulders on the casing and being thereby marred or more seriously damaged so that delay in the sinking of the well resulted and it was necessary to frequently stop the operation 30 of the pump to repair broken parts. The construction devised by me and forming the subject matter of the present application thoroughly overcomes these defects 35 and prolongs the life of the casing as well as the life of the elements operated within the same.

The stated object and such other incidental objects as will hereinafter appear are attained in the device illustrated in the accompanying drawings, and the invention 40 consists in certain novel features which will be hereinafter first fully described and then specifically claimed.

In the drawings, Figure 1 is a side view 45 of a length of a sheet metal tube embodying my invention. Fig. 2 is a longitudinal section of a portion of the tube shown in Fig. 1 with the parts separated. Fig. 3 is a similar view showing the parts joined. Fig. 4 is a longitudinal section of two tube sections jointed in accordance with my invention.

The well casing is formed of a series of tubular sheet metal members or lengths, each 55 of which consists of four sections 1, 2, 3 and 4, as shown in Fig. 1. Each of these

sections is provided near one end with an exterior annular bead, 5, which constitutes a stop to limit the movement of the other section and defines the male end 50. This result is caused by the end of the said other section bearing against the stop bead 5, as will be readily understood, and as shown in Figs. 1 and 3. Near its opposite end each section is provided with a tapering or contracted portion 6 whereby an internal shoulder 7 is provided, which shoulder defines the female end 70 and is adapted to be engaged by the male end of a meeting section when two sections are fitted together. The inner surface of the section will thus present an inclined or tapered surface 8 so that should the drill or the pump rod or other element working within the tube sway to one side it will strike the said inclined surface 8 and be thereby deflected away from the sharp shoulder or edge presented by the end of the inner or engaged section and, consequently, the defacing or cutting of the surface of the working element will be avoided.

Three important advantages are gained by the contracted portion, 6, as follows—the resulting shoulder acts as an internal stop bead to prevent further longitudinal movement of the connecting member, it acts as a deflector by reason of its inclined surface and, it positively protects the otherwise exposed end of the inner tube so that elements moving within meet with no obstruction and cannot come in contact with abrupt edges or surfaces. A fourth advantage is that the contracting of the connecting member results in the inclined surface and shoulder rendering the tube more firm and causes it to retain its round form. The end sections, 1 and 4, of each member or length of the tube are each provided at one end with spirally disposed beads or threads, 9, which are adapted to engage similar beads or threads on the ends of meeting lengths to couple the lengths into a casing or tube, as will be readily understood on reference to Fig. 4.

In constructing a tube according to my invention, the sections 1, 2, 3 and 4 are driven tightly together, as shown in Fig. 1, and the meeting ends secured by rivets 10. The lengths thus produced are shipped to the point where the tube is to be used and there assembled by rotating the end section 1 of one length upon the end section 4 of another length with the threads

9 in engagement whereby the lengths will be drawn together and firmly secured, the longitudinal movement of the members of the joint being limited by the stop bead 5 and the shoulder 7 impinging against the extremities of the meeting members. The male end 50 and female end 70 are of equal length, and the stop shoulder or bead on each simultaneously engages the extremity 10 of the other so that the strain is not concentrated upon one member and telescoping of the members of the joint is positively prevented. The female end of each section 15 beyond the tapering or contracted portion is slightly greater in diameter than the male end so they will fit nicely together. With my construction, the lengths are arranged with the smaller or male end upward, and the female end of the meeting section is 20 fitted over the same so that water which may be running down the outside of the tube will be carried over the joint and prevented from passing through the same into the tube or casing. It will be seen that, 25 when the receiving end of each section bears against the stop bead on the other section it constitutes a seat therefor, the internal deflector 7 serving to overhang the end in the seat and being at its smaller end 30 of an internal diameter equal to the internal diameter of the inner or received end.

While the invention is particularly ad-

vantageous as applied to well casings, it may also be used in down spouts, ventilating tubes, or other tubes. The construction prolongs the life of the tube as well as of the elements operated within the same. 35

Having thus described my invention, what I claim is:

A well casing or the like consisting of a 40 plurality of tubular sections having interfitting male and female portions, said sections being circular in cross section, the 45 being an outstanding annular stop bead on the male portion, and a tapered portion constituting an interior annular deflector in the female portion, the internal diameter of the female portion being substantially equal to the external diameter of the male portion, said female portion bearing against 50 the stop bead and constituting a seat for the male portion, the internal deflector overhanging the male portion and having its smallest internal diameter equal to the internal diameter of the male portion, and 55 means for securing the sections together.

In testimony that I claim the foregoing as my own, I have hereto affixed my signature in the presence of two witnesses.

ALBERT G. FELKER.
